DIESOCK

George Roper, Washington, D. C.

Application March 13, 1944, Serial No. 526,249

3 Claims.

(Cl. 10—123)

This invention relates to a die stock particularly adapted for threading dies.

Its object is to provide a single die stock which will fit dies of different outside diameter.

While dies of practically all makes are standardized as to outside diameter, there may be one size of outside diameter for dies of a certain range of threading capacity, and another size of outside diameter for another range of capacity. Moreover, there are frequently two outside diameters for dies of the same cutting capacity.

At the present time, when tools are scarce, it is frequently difficult to obtain a replacement die having the same outside diameter as the one replaced. This makes it necessary to provide an additional die stock to carry the replacement die.

The subject invention simplifies the situation by providing a single die stock adapted to fit dies of different outside diameters.

Other objects of the invention will appear as the following description of a preferred and practical embodiment thereof proceeds.

In the drawing which accompanies and forms a part of the following specification, and throughout the several figures of which the same reference characters have been used to denote identical parts:

Figure 1 is a plan view of a die stock embodying the features of the invention, the outer portions of the handles being omitted;

Figure 2 is a longitudinal vertical section taken along the line 2—2 of Figure 1;

Figure 3 is a vertical diametrical section taken along the line 3—3 of Figure 1, showing a die in place.

Referring now in detail to the several figures, the subject die stock comprises a body 1 having handles 2, a central socket 3 with an underlying peripheral lip 4, an adapter 5 fitting the socket 3, seated upon the lip 4 and itself having a socket 6 with a peripheral underlying lip 7, and an adapter 8 fitting the socket of the adapter 5, seated upon the lip 7 and itself being provided with a socket 9 having the peripheral underlying lip 10. The sockets are all coaxial and the upper and lower faces of all of the underlying lips as well as the opposite faces 11 and 12 of the body 1, lie in planes perpendicular to the common axis of the sockets.

With all of the adapters in place, as shown, the die stock will take a die 17 of small outside diameter, received in the socket 9. With the adapter 8 removed, it will take a die of intermediate outside diameter received in the socket 6 and with both adapters removed, it will take

a die of large outside diameter received in the socket 3. The selection of two adapters, as shown, rather than more or less than two, is purely arbitrary.

Substantially all dies are standardized to the extent that for a given outside diameter all have the same thickness, also the thickness is proportional to the outside diameter so that dies of smaller outside diameter are less thick than those of larger outside diameter. These factors are of important consideration in the design and construction of the subject die stock.

The body 1 is provided at quadrantly spaced intervals with radial threaded bores 13 receiving the set screws 14. The axes of the set screws are in a common plane perpendicular to the axis of rotation of the die stock and spaced from the plane of the upper face of the lip 4 a distance equal to one half the thickness of the die which fits the socket 3. Since all dies are provided with external diametrically opposite holding pits equidistant from the opposite faces of the die, for receiving the ends of the set screws, a die secured in the socket 3 is reversible, for whichever side of the die is against the lip 4, the pits will be coaxial with the set screws.

The adapters are provided with quadrantly spaced bores 15 and 16, which may be unthreaded, and which are adapted to be brought into alignment for the passage of set screws, and the axes of which bores are in the plane of the axes of the set screws when the adapters are in place.

Since the die which fits the socket 6 is of less thickness than the die which fits the socket 3, its lower face will lie in a plane above the plane of the upper face of the lip 4 when the die is supported with its holding pits coaxial with the set screws 14. The distance apart of these planes is the thickness of the lip 7. The rule is, therefore, that the thickness of the lip of each adapter is one half the difference between the thicknesses of dies whose outside diameters are respectively the diameter of the socket of the adapter and the outside diameter of the adapter.

The purpose of the lips is to provide a support for the inserted adapter or die so that it is automatically stopped in a position in which the axes of the set screw bores in the adapters and/or the holding pits of the die are in the plane of the axes of the set screws, it being only necessary to orient the adapters and die to bring the bores and pits into circumferential registry with the set screws, whereupon the latter may be tightened against the die in the customary manner. Usually, only two opposite set screws enter

pits, the other pair bearing flush against the sides of the die.

When the die with the smallest outside diameter is employed, all of the adapters form part of the die stock. When a larger die is to be employed, one or more of the adapters are removed to make available a socket which the desired die will fit.

As a matter of convenience and economy, it is preferred to make the socket 3 in the body 1 no deeper than the thickness of the die which it is designed to receive. This will bring the upper face of the die flush with the upper face 12 of the body. Since the smaller dies will be of less thickness than the largest die, it is not necessary to make the adapters come flush with the upper face of the body 1, as shown. They need come no higher than the upper face of the dies which they enclose.

It is customary to present the lower face 11 of the die stock to the work. However, as the lower face of the die is more deeply in-set with respect to the body 1 than the upper face, on account of the thickness of the lip 4, in threading close to the head of a bolt, for example, the upper face 12 of the body 1 is presented to the work, in which case the die is reversed in the stock.

The upper and lower faces of the die stock are preferably made planiform throughout, so that they serve as efficient eye gauges in determining the perpendicularity of the die stock with respect to the bolt or rod being operated upon.

While I have in the above description disclosed what I believe to be a preferred and practical embodiment of the invention, it will be understood to those skilled in the art that the specific details of construction and arrangement of parts, as shown and described, are by way of illustration and not to be construed as limiting the scope of the appended claims.

What I claim as my invention is:

1. A die stock comprising a body having a cylindrical socket and a peripheral lip at one end of said socket extending inwardly forming a shoulder, a cylindrical adapter received within said socket having itself a cylindrical socket with an inwardly extending peripheral lip at one end forming a shoulder, said adapter being seated on the first mentioned shoulder, said sockets being coaxial and said shoulders lying in planes perpendicular to said axis, said body and adapter having radial set screw bores with their axes in a common plane perpendicular to the axis of said sockets, the plane of the axes of said bores being spaced from the plane of the shoulder of said body socket a distance equal to half the thickness of a standard die having an outside diameter equal to the diameter of said body socket, and the thickness of the adapter lip being such that the distance between the plane of the axes of

said bores and the plane of the adapter shoulder is equal to half the thickness of a standard die having an outside diameter equal to the diameter of the adapter socket.

2. A die stock comprising a body having a cylindrical socket and a peripheral lip at one end of said socket extending inwardly forming a shoulder, a plurality of nested adapters inserted in said socket the outer of said nested adapters being seated upon the shoulder of said socket, each of said nested adapters having a cylindrical socket and a peripheral lip at one end forming a shoulder at the lower end of its socket, the smaller adapter being seated upon the shoulder of the adapter within which it is received, said sockets being coaxial and said shoulders lying in planes perpendicular to said axis, said body and said adapters having radial set screw bores with their axes in a common plane perpendicular to the axis of said sockets, said common plane being spaced from the plane of the shoulder of said body socket a distance equal to half the thickness of a standard die having an outside diameter equal to the diameter of said body socket, and the thickness of the lips of the respective adapters being such that the distances between said common plane and the planes of the respective adapter shoulders are equal to half the thickness of standard dies having outside diameters equal to the diameters of the corresponding adapter sockets.

3. A die stock for the selective reception of dies, of different size whose thickness varies in direct ratio to the diameter, and having a holding pit in their median diametrical plane, comprising a body having a cylindrical socket with an inwardly extending peripheral supporting lip at one end, the inner face of which lip lies in a diametrical plane, the wall of said socket having a threaded radial aperture therethrough, the axis of which is in a diametrical plane spaced from the plane of said lip a distance equal to half the thickness of the die which fits said socket, an adapter fitting in said socket supported by said lip provided with a cylindrical socket and having an inwardly extending peripheral supporting lip at its inner end, the inner face of which lies in a diametrical plane, the wall of said adapter having a radial aperture registrable with said threaded aperture, having its axis in the diametrical plane of said threaded aperture, the thickness of said adapter lip being such as to space said lip from the diametrical plane of said axis a distance equal to half the thickness of a die which fits the socket in said adapter, and a screw bolt threaded into said threaded aperture adapted to pass through the aperture in said adapter wall and enter the holding pit in a die carried by said adapter.

GEORGE ROPER.
